UNITED STATES PATENT OFFICE.

LUDWIG WOLFFGRAM, OF BROOKLYN, NEW YORK.

ROLLING-MILL FOR SEAMLESS TUBES.

1,234,245.

Specification of Letters Patent. Patented July 24, 1917.

Application filed July 20, 1915. Serial No. 40,828.

To all whom it may concern:

Be it known that I, LUDWIG WOLFFGRAM, a citizen of the German Empire, and a resident of New York, in the borough of Brooklyn, county of Kings, and State of New York, have invented certain new and useful Improvements in Rolling-Mills for Seamless Tubes, of which the following is a specification.

10 This invention relates to rolling mills for seamless tubes, and has for its object to provide an improved mill, by means of which the rollers may be changed to any position desired. More particularly my invention is 15 shown in the accompanying drawings, and will be more fully described hereinafter and finally pointed out in the claims.

In the accompanying drawing,

Figure 1 is a side view partly in section 20 of my improved mill,

Fig. 2 is an end view thereof,

Fig. 3 is a plan view of part of the mill as shown in Fig. 1,

Fig. 4 shows the relative position of the 25 rollers, and

Fig. 5 shows the relative position of two rollers with the mandrel in position, and the mass or block passing between the rollers and over the mandrel to form the seamless 30 tube.

Fig. 6 represents an elevation of the outer end of one of the cylindrical ways, showing the locking means for holding the roller carrier in adjusted position within said cy- 35 lindrical way, parts being broken out.

Fig. 7 represents a diametrical section of said cylindrical way on line 7—7 of Fig. 6, showing a fragment of the adjustable roller carrier disposed therein.

40 Fig. 8 represents a vertical longitudinal section of a casing for this roller mill in which the several ways for the roller mill are angular in form and structurally separate one from the other.

45 Fig. 9 represents an end elevation of the right hand end of the casing shown in Fig. 8.

Similar reference numerals indicate corresponding parts throughout the several figures of the drawing.

50 Referring to the drawings, and more particularly to Fig. 1, a base 10 is provided which supports two horizontally and laterally extending portions or casings 11 and 12, and an upright or vertically extending portion or casing 13. The casings 11 and 12 are disposed apart from each other in rightline

alignment on opposite sides of the roll pass and are open at their adjacent ends. The casing 13 is disposed at right angles to the axis of the casings 11 and 12. Within each 50 of these portions or casings 11, 12 and 13, which act as guideways, drums 15, 16 and 17 are provided which are capable of being rotated within the portions 11, 12 and 13, and of being moved along the length of the 55 same toward or from each other. Each of these drums 15, 16 and 17 constitute roller carriers, being provided at their forward ends with supporting members 18, which are provided with openings or bearings 19 for corresponding shafts 20 of rollers 21, 22 and 23. The axes of the rollers 21 and 22 are at right angles to the common axis of the carriers 15 and 16 and oscillatable in parallel vertical planes. The axis of the 70 roller 23 is at right angles to the axis of its carrier and is oscillatable in a horizontal plane. These rollers are shaped as indicated in Figs. 3 and 5, and have definite configurations and definite angles, as more fully described in a copending application Serial 80 No. 37,609 filed by me July 1, 1915. The mandrel 25 with the mandrel rod 26 is arranged in a suitable position in respect to the rollers 21 and 22, as shown in Fig. 5, 85 and a mass or block 27 passes through the rollers and over the mandrel 25 to form a seamless thin walled tube 28, as shown in Fig. 5.

The heads 33 at the outer ends of the portions or cylinders 11, 12 and 13 are provided with central screw-threaded openings 33' and screwthreaded stems 31, 32 and 30 engage said openings. The stems 31 and 32 are provided outside said heads with actuating hand wheels 35 and 36 respectively and the stem 30 is provided with an actuating gear wheel 37. The stems 31, 32 and 30 are provided at their inner ends with enlargements 31^a, 32^a and 30^a which engage 95 the outer ends of the drums 15, 16 and 17 in such manner that the drums must move longitudinally within their respective cylinders in unison with such movements of the screwthreaded stems, but the stems and 100 drums are free to turn independently of each other. By rotating any of these wheels in either one or the other direction, the stems are rotated, and by means of the screw-threads the stems are moved in respect to the heads so as to move the drums 105 inwardly or outwardly. At the same time,

when it is desired, the drums may be rotated in their angular position so as to change the angular position of the rollers supported by the drums. For this purpose, each drum is provided with projecting members 38^a which move in guide grooves 39, clearly seen in Figs. 2 and 3, and the object of these is to rotate the drums in a secure manner, and hold them in position and prevent them from wabbling by a suitable locking device. which is adjustable and shiftable on the heads. Any suitable locking device may be employed for this purpose. A convenient locking device is shown in Figs. 6 and 7. The head 40, which corresponds to either of the heads 33 of the other figures has the arc-shaped slots 39 disposed at diametrically opposite points through which the rods 38^a of the drum project. The head 40 is also provided on opposite sides of each of said slots 39 with fixed studs 41 and 42 which are screwthreaded at their outer ends and provided with nuts 43 and 44. Slidable locking plates 50 are each provided with a hole through which the rod 38^a projects and on opposite sides of said hole with concentric arc-shaped slots 52 and 53 which engage the fixed studs 41 and 42. The nuts 43 and 44 are tightened to clamp the locking plates 50 against the head 33 when the drum is adjusted to the desired position and a loosening of these nuts permits the locking plates to slide on said head as the drum is rotatively adjusted. The portions 11, 12 and 13 may be of one piece as shown in Fig. 1. The upper drum 17, in the upper portion 13, requires for convenience sake, a train of mechanism constituting the bevel gears 37 and 38^b, so as to make the operative wheel 34 convenient of operation.

Figs. 8 and 9 show the casings forming the ways for the roller carriers structurally separate from one another and suitably joined together. These figures also show the casings, forming ways for the roller carriers, in rectangular instead of in cylindrical form. The rectangular casings 11^a, 12^a and 13^a correspond to the cylindrical casings 11, 12 and 13 of the other construction. Any form of casings and carriers suitable for carrying out the invention may be used.

I have shown various embodiments of my invention, but it is clear that changes may be made therein without departing from the spirit thereof as defined in the appended claims.

Having thus described my invention, I claim as new and desire to secure by Letters Patent:—

1. A rolling mill comprising two cylindrical ways open at their inner ends and disposed in rightline alinement, roller carriers movable therein toward and from each other and provided with bearings at their adjacent ends, rollers journaled in said bearings and

having their axes at right angles to the axis of said carriers, the axes of said rollers being oppositely inclined in parallel planes, means for adjusting said carriers toward or from each other to change the distance between said rollers, and means for turning said carriers to shift said rollers into different inclines in their parallel planes. 70

2. A rolling mill comprising two ways disposed in rightline alinement, a third way 75 extending outward at right angles to said two ways at the inner ends thereof, roller carriers movable in said alined ways toward and from each other and provided with bearings at their adjacent ends, rollers journaled in said bearings and having their axes at right angles to the axis of said carriers, the axes of said rollers being oppositely inclined in parallel planes, means for adjusting said carriers toward or from each other to change 80 the distance between said rollers, means for turning said carriers to shift said rollers into different inclines in their parallel planes, a roller carrier movable in said right angled way and provided with bearings at 85 its inner end, a roller journaled in said last named bearings and having its axis at right angles to the axis of its carrier, means for adjusting said last named carrier inward and outward within said third way, and means 90 for turning said third carrier to shift its roller with relation to the other rollers. 95

3. A rolling mill comprising two ways disposed in rightline alinement, a third way 100 extending outward at right angles to said two ways at the inner ends thereof, roller carriers movable in said alined ways toward and from each other and provided with bearings at their adjacent ends, rollers journaled in said bearings and having their axes at 105 right angles to the axis of said carriers and the axes of said rollers being oppositely inclined in parallel planes, means for adjusting said carriers toward or from each other to change the distance between said rollers, 110 means for turning said carriers to shift said rollers into different inclines in their parallel planes, a roller carrier movable in said right angled way and provided with bearings at 115 its inner end, a roller journaled in said last named bearings and having its axis at right angles to the axis of its carrier, means for adjusting said last named carrier inward and outward within said third way, means for turning said third carrier to shift its 120 roller with relation to the other rollers, and means for locking said carriers to hold said rollers at their several adjusted positions.

4. A rolling mill comprising two cylindrical ways disposed in rightline alinement, 125 open at their inner ends and provided at their outer ends with heads having arc-shaped slots, cylindrical roller carriers turnable in said ways, movable therein toward and from each other and provided at their 130

- adjacent ends with bearings and at their outer ends with studs adapted to engage said slots, rollers journaled in said bearings and having their axes at right angles to the 5 axis of said carriers, the axes of said rollers being oppositely inclined in parallel planes, means for adjusting said carriers toward or from each other to change the distance between said rollers, and means for turning 10 said carriers to shift said rollers into different inclines in their parallel planes.
5. A rolling mill comprising two cylindrical ways disposed in rightline alinement, a third cylindrical way extending outward 15 at right angles to said two cylindrical ways at the inner ends thereof, roller carriers movable in said alined ways toward and from each other and provided with bearings at their adjacent ends, rollers journaled 20 in said bearings and having their axes at right angles to the axis of said carriers, the axes of said rollers being oppositely in-
- clined in parallel planes, means for adjusting said carriers toward or from each other to change the distance between said rollers, 25 means for turning said carriers to shift said rollers into different inclines in their parallel planes, a cylindrical roller carrier movable in said right angled way and provided with bearings at its inner end, a roller journaled 30 in said last named bearings and having its axis at right angles to the axis of its carrier, means for adjusting said last named carrier inward and outward within said third way, and means for turning said third carrier to 35 shift its roller with relation to the other rollers.

In testimony that I claim the foregoing as my invention, I have signed my name in presence of two subscribing witnesses.

LUDWIG WOLFFGRAM.
